UNITED STATES PATENT OFFICE.

ROBERT W. HARDIE, OF LARCHMONT, NEW YORK.

AIR-MOISTENER.

1,151,938.

Specification of Letters Patent. Patented Aug. 31, 1915.

Application filed January 13, 1915. Serial No. 1,988.

To all whom it may concern:

Be it known that I, ROBERT W. HARDIE, a citizen of the United States, residing at Larchmont, in the county of Westchester and State of New York, have invented new and useful Improvements in Air-Moisteners, of which the following is a specification.

This invention relates to means designed to humidify the atmosphere of a room or building. It is a well known fact that atmosphere in its normal condition should contain a certain percentage of humidity relatively to the temperature of the atmosphere, and that atmosphere at a high temperature will hold and require a larger percentage of humidity than atmosphere of a lower temperature. When air is taken into a building from the outside during cold weather, it is of low temperature and contains normally a lower percentage of humidity than air at a higher temperature. When the air taken in from the outside of a building is heated artificially, the temperature of the air is increased but the humidity is not increased. The percentage of humidity relative to the temperature is materially lessened, and therefore the air when so heated becomes too dry for the health or comfort of the occupants of the room. The result is that the air becomes deprived of humidity to such an extent as to have an injurious effect on the glands and respiratory organs of the human body, and the injurious effects of air in that condition extend even to the furniture and woodwork of the room causing it to dry out and crack.

The principal object of this invention is to provide what may be regarded as the approximate normal percentage of humidity relative to the temperature of the air in a room or building.

In the accompanying drawings showing one embodiment of the invention, similar reference symbols indicate corresponding parts throughout the several views.

Figure 1 is a side elevation, partly broken away, of a device embodying my invention, inclosed by a partially open casing, one side of which is removed. Fig. 2 is an end elevation of the device shown in Fig. 1 with one end of the casing removed. Fig. 3 is a plan of one of the trays shown in Fig. 1, and Fig. 4 is a vertical transverse section taken on the line 4-4 of Fig. 1.

As illustrated in the drawings, a plurality of sections or units are arranged one

above another, and spaced apart, each section comprising a heater and a tray arranged in close proximity to its corresponding heater.

The heaters, or heat radiating members 1, are shown as longitudinal bodies having a hollow interior adapted to receive steam or hot water, the interior of said members communicating by means of pipe connections 2 and 3, with a source of heat supply. The radiating members or heaters may be supported in any suitable manner, such as by means of brackets 4. Studs or bearing blocks 5 may be formed on or placed between the heaters to aid in supporting one member on another if desired. Trays 6 are arranged between said heaters, each tray in close proximity to a corresponding heater.

The trays are preferably shallow and substantially broad, and are designed to hold and expose to the air water in any desired quantities; and to that end pockets or chambers of any suitable number, form and dimensions may be formed therein by means of corrugations or ribs 7. The corrugations also increase the area of the heating surface in direct contact with the water in the trays. The trays are preferably provided with lateral marginal ribs 8, and an end rib 9, to prevent water from flowing off the trays at any point other than at the discharge or overflow end.

In the preferred form of my invention, the overflow from one tray passes on to the next lower tray, and if desired the discharge end of the trays may be provided with a rib or flange 10 to aid the water in dripping from one tray on to the tray below. In that manner a plurality of trays may be supplied with water from the top tray.

By arranging the respective trays in close operative relation to their corresponding heaters, and spacing apart the respective sections, comprising a heater and a tray, each heater heats the water in its corresponding tray and heats the air above the water in the tray below. And as the capacity for absorbing moisture is increased by raising the temperature of the air, the air so heated evaporates the water from the trays quickly and with a minimum expenditure of heat.

It is not essential that the heat radiating members, or the trays be of the construction shown and described, provided that the trays be each in close proximity to its cor-

responding heater, and be capable of holding a predetermined quantity of water, and in their preferred form, communicate one with another in downward sequence.

5 The surplus water from the series of trays may, if desired, overflow into a tank or receptacle 11, provided with an overflow pipe 12 leading to any desired outlet or receptacle.

10 To compensate for the evaporation of water from the trays a pipe connection 13 is made between a source of water supply and the trays, and provided with a valve 14 by means of which the quantity of water 15 furnished to the trays may be regulated in proportion to the quantity being evaporated from the trays, and keep the trays filled with water to the overflow depth. Thus at night, and at other times, when the temperature of the heat radiating members is reduced, the supply may be reduced by the valve 14, or increased thereby, when the temperature of the heat radiating members, and consequently the evaporation from the trays 25 is increased. The supply pipe 13 may be used in connection with a receiving tank 15, provided with perforations 16 to permit water to drip on to the uppermost tray. But that is not essential. The tank may be dispensed with, and the water delivered from the supply pipe directly on to the trays.

30 The trays and heat radiating members, may when so desired, be inclosed within a 35 casing having openings, or an openwork construction that will permit the air to pass through, to the desired extent.

What I claim as new and desire to secure by Letters Patent is,

1. In an air moistener, the combination of 40 a series of heat radiating members arranged one above another, and a plurality of trays arranged respectively between said members each tray in close proximity to a corresponding heater, whereby each of said heat- 45 ing members heats the water in its corresponding tray, and heats the air above the water in the tray below.

2. An air moistening apparatus comprising 50 a plurality of sections arranged one above another and spaced apart, each section having a heat radiating member and a tray arranged in close proximity to said member, the trays being provided with means permitting an overflow therefrom above a 55 predetermined depth, and means for keeping said trays supplied with water to the overflow depth.

3. In an air moistening apparatus, the 60 combination of a plurality of sections arranged one above another, and spaced apart each section having a heat radiating member and a tray arranged in close proximity to said radiating member, the trays being provided with means permitting an overflow therefrom above a predetermined depth, the bottoms of said trays being 65 corrugated to increase the heat conveying surface, and means for supplying water to said trays.

ROBERT W. HARDIE.
